UNITED STATES PATENT OFFICE.

FREDERICK A. PRATT, OF BUTTE, MONTANA, ASSIGNOR OF TWO-THIRDS
TO CLEMENT BARTZEN AND ARTHUR H. WETHEY, OF SAME PLACE.

ORE-SEPARATOR.

SPECIFICATION forming part of Letters Patent No. 639,433, dated December 19, 1899.

Application filed May 16, 1899. Serial No. 717,110. (No model.)

To all whom it may concern:

Be it known that I, FREDERICK A. PRATT, a citizen of the United States, residing in Butte, Silver Bow county, Montana, have invented 5
certain new and useful Improvements in Ore-Separators, of which the following is a specification, reference being had to the accompanying drawings, forming a part hereof.

This invention relates to apparatus employed in the concentration of ores for the purpose of separating the fine particles of crushed ore from the coarser particles. Various devices have been suggested or employed for this purpose—such as revolving 10 screens, hydraulic sizers, &c.—and while some have been used in the absence of any better device they are all more or less open to objection.

It is the object of this invention to produce 15 an improved device or machine for the purpose referred to which shall be simple and inexpensive both in construction and in operation, shall not be liable to become clogged or blinded in use nor to the consequent reduction 20 of capacity of the machine, shall be capable of treating large quantities of ore in a given time, and shall effect a thorough separation, not permitting the fine particles to pass along with the coarse, and thereby necessitate 25 repeated working over of the ore. In the improved machine the screen is stationary and is disposed in funnel form around a rapidly-revolving distributer. The fine particles pass 30 through the screen into a surrounding receptacle, while the coarse particles drop down 35 through the open bottom of the funnel.

The invention will be more fully described hereinafter with reference to the accompanying drawings, in which, for purposes of explanation, it is illustrated as embodied in a 40 convenient structure.

In the drawings, Figure 1 is a vertical central section of a machine which embodies the invention. Fig. 2 is a plan view of the same, 45 a portion of the casing being removed. Fig. 3 is a plan view of the same with the hopper and driving-pulley removed and the distributing-spouts broken off.

As represented in the drawings, the mechanism is supported by a suitable framework 50 A, the sides of which are inclosed by a suit-

able sheathing B. Within the frame and sheathing is supported a conical screen C, which may be of any suitable material and of any suitable mesh. In the drawings the upper part of the screen is shown as formed of a perforated plate, the size of the apertures being exaggerated for convenience in drawing, and the lower part of the screen is represented as formed of wire. A dished diaphragm D is shown as forming a sort of floor within the screen, such diaphragm having an opening d in its central and lowest part. A vertical shaft E, having a suitable driving-pulley e, is supported in suitable bearings 55 centrally with respect to the funnel-shaped screen and carries two buckets or distributers F and F', the one above the diaphragm D and the other below the same. The upper bucket F is preferably divided by vertical partitions 60 f into separate compartments, the floors f' of two of the compartments being arranged at different heights above the floor of the first compartment, which is also the main floor or bottom of the bucket or distributer. In the outer 65 wall of each compartment, just above its floor, is an opening f², through which the ore is thrown, in the rapid rotation of the distributer, against the screen, and the arrangement of separate compartments with floors and openings at different heights insures a proper and even distribution of the ore over the surface 70 of the adjacent screen without loading the distributer. It is evident that without any other parts than those just referred to the 75 ore will be thrown against the screen at all times with the same force, depending upon the rapidity of rotation of the distributer; but in order to permit the force with which the ore is thrown against the screen to be 80 regulated and controlled to some extent, as the character of the ore and other conditions may render desirable, each opening is provided with a delivery-pipe f³, having an extensible section f⁴, which can be secured by 85 friction in adjusted position, and thereby regulate to some extent the force with which the material is thrown against the screen, thus preventing unnecessary wear on the screen and also preventing the clogging or 90 blinding of the screen. The lower distributer or bucket F' is represented as having a 95 100

single compartment and a single extensible delivery-pipe, as already described with reference to the upper distributer; but obviously it might have more compartments and 5 delivery-pipes if desired.

A hopper G or any other suitable means may be provided for delivering the material to the upper distributer F. As the latter is rotated at a high speed, the material will be 10 thrown forcibly against the screen C. The fine particles will pass through the same and will fall upon the inclined floor A and thence will pass into the chute or receptacle indicated at A². The coarse particles will pass 15 down through the opening d in the dished diaphragm D into the lower distributer F'. From this the material will be thrown against the screen, and any fine particles that may have passed along with the coarse will go 20 through the screen upon the floor A'. The coarse particles will fall down through the open bottom of the funnel-shaped screen, which is extended through the inclined floor A', and will pass into the chute C', from which 25 they can be taken to the rolls to be reground.

It will be obvious that the improved machine can be driven with a comparatively small amount of power and yet is capable of treating thoroughly a large amount of material in a given time. There are no parts to 30 get out of order, and if it should be necessary at any time to renew the screen the old screen can be removed and a new one placed in po-

sition without difficulty. There is no danger that the screens will become blinded, and the 35 capacity of the machine therefore will not be diminished in use. Furthermore, the improved machine is compact and takes up considerably less space than other machines intended for the same purpose. 40

I claim as my invention—

1. A machine for separating ores comprising a funnel-shaped screen and a rotating bucket or distributer centrally disposed within said screen, said bucket or distributer having an opening in its side wall and an extensible delivery-pipe through which the material is thrown against the screen, substantially as shown and described. 45

2. A machine for separating ores comprising a funnel-shaped screen and a rotating bucket or distributer centrally disposed within said screen, said bucket or distributer being divided by partitions into separate compartments, said compartments having floors 50 at different heights, and each of said compartments having an opening in its side wall above its floor through which the material is thrown against the screen, substantially as shown and described. 55

This specification signed and witnessed this 6th day of May, A. D. 1899.

FREDERICK A. PRATT.
